UNITED STATES PATENT OFFICE.

EMIL GATHMANN, OF BALTIMORE, MARYLAND.

APPARATUS FOR MOLDING INGOTS.

Application filed March 10, 1928. Serial No. 280,809.

This invention relates generally to the art of casting metallic ingots and particularly to apparatus for conserving the heat contained in the molten mass in its upper portion until the cooling and solidification of the ingot has progressed from the bottom thereof upwardly to its upper portion, thus assuring the complete solidification of the entire molten ingot mass without the formation of an upper-air-chilled skin. While my present invention may be advantageously employed in the making of many kinds of ingots, it is best adapted to the molding of slab ingots of the kind shown in my U. S. Patent No. 1,616,039 of Feb. 28, 1928. The ingots may be cast and handled prior to treatment in accordance with my invention in any suitable way.

Any well known method may be employed in the casting of ingots in vertical molds but in the casting of ingots in horizontally arranged molds I prefer to employ the method and apparatus shown and described in my co-pending application for patent Serial No. 214,584 filed Aug. 22, 1927 although my present invention is not limited to the use of such method or apparatus.

Heat-insulating material, both refractory and combustible, has heretofore been applied to the upper portion of ingots in a molten or semi-molten state for the purpose of retarding solidification of this part of the ingot and thus provide liquid metal to compensate for the shrinkage in volume from the liquid to the solid state, thereby preventing the formation of pipe or shrinkage cavities, but this has always been done manually and in more or less of a haphazard manner, the heat-insulating material being used but once. My present invention provides for the systematic and effective covering of the upper surface of the steel while liquid and for the removal of the insulating material after the ingot has solidified but before it is lifted or dumped from the mold.

I preferably employ as a heat-insulating material a finely divided refractory substance, such as infusorial earth, powdered lime, or the like. While these substances are satisfactory non-conductors of heat, their use heretofore has been objectionable because of the inconvenience and dangers which they cause to the operatives, due to the flotation in and the pollution of surrounding air during the handling of the ingots and particularly during the removal of

the ingots from the molds. These objections to the use of such heat-insulating material for the purposes specified are entirely obviated by my invention which involves the employment of methods and apparatus whereby finely divided heat-insulating material is maintained in a reservoir and deposited on the ingots without manual handling and is then after suitable intervals removed from the ingots and returned to the reservoir for reuse. The material is moved through a closed conveyor and is at all times prevented, while passing from reservoir to ingots or from ingots to reservoir, from becoming clouded in the atmosphere in which the steel crew work.

More specifically, the upper free face of the liquid which forms the ingot should be covered promptly after it has been teemed into the mold with the heat-insulating material, which is preferably of a refractory nature and in a finely divided condition. This will cause the upper face of the ingot to be maintained in a liquid or semi-liquid condition until the remainder of the ingot has solidified. After the solidification of the ingot in this manner, the finely divided heat-insulating material is withdrawn from the upper face of the ingot in such manner that it will not cloud the surrounding atmosphere, and it is then deposited in or conveyed to a suitable receiver from which it can again be deposited on another liquid ingot. This cycle of operations may be repeated without substantial loss of the material.

In this way not only is the steel completely protected but as the material is supplied to the ingots in definitely regulated quantities, the nature of the solidified ingot is materially improved.

My improvements are illustrated in the accompanying drawings which are largely diagrammatic.

Figure 1 shows a longitudinal section of an apparatus designed for the purposes hereinbefore mentioned.

Figure 2 is a perspective view of one type of ingot in the making of which my invention may be employed.

Figure 3 is a view partly in end elevation and partly in vertical section of the hopper or reservoir shown in Figure 1.

Figure 4 shows a section on the line 4—4 of Figure 1.

The molds employed are preferably of the

kind shown in my U. S. Patent 1,661,039 of Feb. 28, 1928, although other types of molds may be used.

As shown in the accompanying drawings, 5 each mold M consists of an iron box-like structure open at the top and having heavy bottom walls with side walls which gradually decrease in thickness from bottom to top. The bottom walls are cambered as indicated for purposes described in my patent 10 above mentioned. The drawings show a series of molds mounted on or secured to a conveyor C which may be of any construction suitable for specific installations and 15 practices.

The drawings show only a portion of the conveyer but it will be understood that it is an endless conveyer and may be driven in any suitable way so as to carry the ingot 20 containing molds beneath the apparatus which supplies and withdraws the heat-insulating material. The conveyor is moved forward step-by-step.

The apparatus shown consists of a closed 25 hopper or reservoir A containing a finely divided or dust-like heat-insulating material B. This material may be maintained in a heated condition by electrically heated coils D or in other suitable ways. The hopper 30 has a discharge spout E at the upper end of which is mounted a riddle or screen F which is adapted to reciprocate in a horizontal plane on guides f. The mesh of this screen should be such that when the screen 35 is stationary, i. e., is not being vibrated, the refractory material, due to its natural packing tendency, will not pass through the screen. The screen is adapted to be moved back and forth by cams G which are so 40 shaped and so operated as to give the screen a step-by-step or intermittent movement. The cams may be mounted on shafts g which are operated in any suitable way as by gearing g' (Fig. 1). Any other suitable mechanism 45 for vibrating the screen may be employed.

A funnel-shaped receiver H is located 50 above the conveyor C a suitable distance from the spout E and this receiver is connected by a pipe or conveyer J to a fan K driven by a motor L. The fan is connected with the upper portion of the hopper A by a short pipe N provided with a valve O which may be used to control the passage of the 55 material from the conveyer to the hopper. The pipe N is provided with an outlet branch pipe P equipped with a valve Q. This pipe P may be used in charging the hopper with the heat-insulating material 60 or it may be employed as a by-pass for exhausting the pressure when material is not being conveyed.

It will be understood that the depositing 65 and the recovery of the heat-insulating material is an intermittent operation. The con-

veyor is moved intermittently or step-by-step and the screen F is operated intermittently, the material being passed through the screen when a mold containing molten metal for forming the ingot is at rest below 70 the spout E. When a mold with its ingot reaches the receiver H, the insulating material is withdrawn.

The amount of heat-insulating material in the hopper should at all times be sufficient 75 to cover a series of ingots though not necessarily a complete heat. No large additions to the hopper should normally be necessary as most of the material is recovered from the solidified ingots.

By depositing finely divided or comminuted heat-insulating material, such as infusorial earth, powdered lime, or the like, on the forming ingots and retaining it there a suitable time, I maintain on the upper face 85 of the ingot its approximate temperature as cast until cooling or solidification has progressed from its bottom to its upper face, thus preventing the formation of double skins, shrinkage cavities, cold shuts or 90 roughened surface zones and also lessening the oxidation of said surface during the cooling and solidification period. The interval of time between the application of heat-insulating material to the ingot and its 95 removal therefrom is governed primarily by the size (largely the depth) of the ingot being produced.

The ingots may be removed from the molds by various methods now well-known 100 to those skilled in the art.

The ingot I shown in Figure 2 has its bottom portion i inwardly cambered and its top portion i' slightly depressed at its longitudinal axis. The depth of the ingot is 105 considerably less than its width and the length is greater than said width. An ingot of this contour, the upper face of which has been kept liquid so that solidification occurs through progressive cooling from the bottom to the top, is entirely free from pipe or shrinkage cavities as well as porosity if the molten metal has been suitably finished and degasified. Roughened patches or "snakes" are entirely eliminated and there 115 is very little if any oxide film so that the ingots are commercially usable in their entirety less the usual scale and end crop losses.

Due to the relatively thin vertical section of an ingot of this type, segregation of the metalloids is very slight as segregation is substantially proportional to the time of solidification and solidification is proportional to the least vertical dimension of the ingot.

Many modifications in the apparatus for applying and removing the heat-insulating material may obviously be employed without departing from the scope of my invention.

Not only are better ingots produced by my invention but, as before stated, the heat-insulating material may be used over and over and will not foul the atmosphere.

5. I claim as my invention:

1. An apparatus for producing sound ingots comprising a reservoir for heat-conserving material, means for depositing material from said reservoir on the upper face of 10 ingot metal and means for retrieving said material from the ingots for further use after the ingots have completely solidified.
2. An apparatus for producing sound ingots comprising a reservoir for heat-conserving material, means for heating said material, means for depositing it on the upper 15 face of ingot metal and, means upon solidification of the ingot, for retrieving said material for further use.

3. An apparatus for producing sound ingots comprising a reservoir for heat-conserving material, means for depositing material from said reservoir on the upper or free face of molten ingots, means for retrieving said material after solidification of 25 the ingots has been accomplished and means for returning it to the reservoir from which it was originally supplied to the ingot.

4. An apparatus for producing sound ingots comprising a reservoir for heat conserving material, means for depositing material from said reservoir on the upper face of an ingot metal, and pneumatic means for retrieving said material from the ingots.

In testimony whereof, I have hereunto 35 subscribed my name.

EMIL GATHMANN.
